Primary Examiner — Karen S Acker*Assistant Examiner* — Elizabeth S Ko(74) *Attorney, Agent, or Firm* — Oblon, McClelland, Maier & Neustadt(57) **CLAIM**

The ornamental design for a pivot support, as shown and described.

DESCRIPTION

FIG. 1 is a top perspective view of a pivot support according to our design;

FIG. 2 is a top plan view thereof;

FIG. 3 is a front view thereof;

FIG. 4 is a back view thereof;

FIG. 5 is a left side elevational view thereof;

FIG. 6 is a right side elevational view thereof;

FIG. 7 is a bottom perspective view thereof;

FIG. 8 is a bottom plan view thereof; and,

FIG. 9 is a bottom perspective view thereof, in a position of use with an unclaimed bottom of a dump body.

The broken lines depict portions of the pivot support that form no part of the claimed design.

Additional broken lines in FIG. 9 depict environmental subject matter that forms no part of the claimed design.

1 Claim, 9 Drawing Sheets(56)
